Attorney.

UNITED STATES PATENT OFFICE

2,685,929

COMBINED STAPLE REMOVER AND PUNCH

Walter Faas, West Orange, N. J., assignor to The
Bates Manufacturing Company, Orange, N. J.,
a corporation of New Jersey

Application January 27, 1951, Serial No. 208,095

2 Claims. (Cl. 164—121)

1

The invention relates to improvements in a combined staple remover and punch of the portable hand operated plier type.

A prime object of the present invention is to provide a device of this kind that can easily and conveniently be used for the removal of clinched and unclinched staples from papers, drawing boards or the like, and for punching holes in papers or the like.

Another object of the invention is to provide a device of this kind with means for stripping the paper or the like from the punch.

Another object of the invention is to provide a device of this kind that will readily remove staples of various sizes, without tearing or mutilating the papers to which the staples may have been applied.

Another object of the invention is to provide a device of this kind that has a minimum number of parts, is easy to assemble, is inexpensive to manufacture, and is reliable in use.

Other objects and advantages of the invention will be apparent from the description thereof to follow taken in connection with the accompanying drawing in which—

Figure 1 is a side elevational view of a combined staple remover and punch embodying my invention, the parts being shown in normal open position.

Figure 2 is a similar view showing the parts in closed position.

Figure 3 is a horizontal sectional view taken on the plane of the line 3—3 of Figure 2.

Figure 4 is a horizontal sectional view through the handle members showing them in one position during the removal of a staple which is shown in top plan view.

Figure 5 is a horizontal sectional view approximately on the plane of the line 5—5 of Figure 1.

Referring to the drawing in detail, the improved device is of the plier type including a pair of elongated handle members 1 and 2 that cross each other at one end and are connected by a pivot pin 3 for pivotal movement toward and away from one another. The handle members 1 and 2 are channel construction or U-shaped in transverse section providing side flanges 4 and 5 and 6 and 7, respectively, making the device more rigid and stronger and easier to grasp. The handle member 1 is formed with a jaw member 8 adjacent the pivot, and handle member 2 is formed with a similar jaw member 9 opposite jaw 8.

The handle member 1 is slotted as indicated at 10 to permit the handle member 2 to extend

2

therethrough and its flanges 4 and 5, adjacent the pin 3, are spaced apart a distance such that the flanges 6 and 7 of handle member 2 may enter between them. The face of the jaw member 8 of handle member 1 carries a tubular punch member 11, circular in cross-section, projecting toward the face of the jaw member 9. The opposite face of jaw member 9 of handle member 2 is formed with an opening forming a die 12 adapted to receive the punch member 11.

A coil spring 13 surrounds the pivot pin 3 and has the elongated free arm portion 14 impinging against the inner surface of handle member 2 to constantly urge the handle members in directions to carry their jaw members, mounting the punch and die members, away from one another, thereby leaving a space between said punch and die for receiving the paper or the like to be punched. When the handle members 1 and 2 are pressed or squeezed together by the fingers of the operator, the punch member 11 will pass through the paper and into and through the die member 12 thereby forming a hole in the paper.

The spring 13 has its other free arm portion 15 shaped in the form of a loop 16. The loop loosely encircles the punch member 11 and is normally positioned adjacent the outer end thereof with its free end 17 projecting into the space between the punch and die members and constantly urged to such position by the spring arm 15, which intermediate its length engages an abutment 15a on the jaw 8. Upon the working stroke of the punch member, the projecting end 17 of the loop first engages the paper being punched thereby clamping and holding the paper on the paw 9, and at the same time the loop is pressed inwardly along the punch member 11 as shown in Figure 2, the loop being held in its innermost position on the punch member by the jaw 9 during said working stroke. When pressure on the handles is released, the spring arms 14 and 15 force the punch and die members apart. At the same time, the loop 16 is slid over the punch member by the spring arm 15 thereby stripping the paper from the punch 11, the free end 17 pushing the paper beyond the end of the punch. The loop is thus retracted and returned to position for operation under a succeeding working stroke of the punch.

The handle member 2, at the end opposite its jaw 9, is formed with a flange 18 projecting inwardly toward the handle member 1. The side edges 19 of the flange diverge on curved lines and form a blunt pointed free end 20 having a knife edge. Thus the over-all distance between

the side edges of the flange increases as we move back from its end 20 as shown in Figure 4. The flange is longitudinally curved and this curvature is of a radius having the pivot pin 3 as its center or axis.

The handle member 1 is slightly shorter than the handle member 2 and its end, opposite the jaw 8, is formed with a straight plate member 21 extending at right angles to the handle member and projecting inwardly toward the handle member 2. The plate member is formed with inwardly extending flange portions 23 and 24 and terminates in a blade 25. The blade is substantially the width of the end 20 of flange 18 and extends in substantially the same direction as handle member 1. When handle member 1 is moved, the outer edge of the blade travels in an arc that has the pivot pin 3 as its center or axis and that is slightly smaller in diameter than the arc over which the flange 18 travels. This permits the outer edge of the blade to travel along and over the inner surface of the flange 18 when the handle members are moved toward or away from one another.

When using the device as a staple remover, the sheets of paper or the like, from which it is desired to remove the staple or staples, are preferably placed on a horizontal support. The handle members 1 and 2 are grasped by the fingers of the operator and the device held in a vertical position. The handle member 1 is first placed on the surface of the paper and tilted slightly so that the corner 22 and the outer edge of blade 25 rest on the surface of the paper, with the outer edge of the blade placed to one side and in engagement with the crown or cross bar 26 of the staple to be removed. The blade contacts said crown for substantially its entire length. The handle member 2 is then swung inwardly toward the handle member 1 whereby the flange 18 of handle member 2 is swept under the under side of the crown 26 of the staple. The flange 18 will have entered under the staple crown a distance depending upon the width of the crown, and the side edges 19 of the flange will be in engagement with the inner sides of the staple legs immediately adjacent the crown. Pressure is now exerted upon the handle member 1 to force said handle member toward the handle member 2 whereby the blade 25 will distort the staple and force its crown 26 over the inner surface of flange 18, while the legs of the staple are dragged over the side edges 19 of the flange. This results in

a slight widening of the crown of the staple and partial straightening of the legs. Continued rearward pressure on the handle member 1 will lift the staple entirely clear of the paper to which it was applied.

During this operation, the outer surface of the flange 18 rests on the top surface of the paper and supports the paper or holds it so that it is not drawn up by the legs of the staple and so that the legs of the staple are readily and completely removed from the paper without tearing the paper.

Since the flange 18 of the handle member 2 has a tapered free outer end, the device is adapted 15 for the removal of staples of various sizes.

Changes in details of construction might be made without departing from the principle of the invention.

What I claim is:

1. A handle punch comprising a pair of crossed-handle members having jaws at their corresponding ends, a pin pivotally connecting the handle members intermediate their ends, a punch member carried by the jaw of one of said handle members, the jaw carrying said punch member having an abutment thereon between said punch and said pin, a die carried by the jaw of the other of said handle members and co-acting with the punch member, a helical spring supported by said pin having one end portion engaging said abutment and having another end portion engaging the other handle member, the first mentioned end portion of said spring terminating in a loop at the side of said abutment opposite said pin with the loop encircling said punch member and movable longitudinally thereof to strip a work piece from said punch member.

2. A hand punch as defined in claim 1 wherein said loop has a free end projecting laterally of the loop toward the opposite jaw and beyond the end of the punch member.
